UNITED STATES PATENT OFFICE

2,207,614

SURGICAL DEVICE

Simon Irving Copen, Boston, Mass.

Application December 9, 1938, Serial No. 244,743

3 Claims.

(Cl. 2-21)

The present invention relates to a surgical dressing and more particularly to a device such as described in my Patent No. 2,138,626, issued November 29, 1938, filed under Serial No. 214,177, 5 in which there is described a surgical finger or cover having in combination therewith an elastic band or ring which may be drawn over the cover and exert pressure, not only to hold it in place, but also to make a more perfect seal between the 10 covered element and the cover itself.

The present invention is an improvement over this device particularly in the construction and application of the ring to the cover or protective device. The improvement is for the purpose of 15 allowing the element to be more readily placed and applied in its use. Other purposes will more readily appear from the description given below in connection with the drawing, in which—

Figure 1 shows the invention in elevation.

Figure 2 shows a fragmentary view of the invention with a modification of the form shown in Figure 1.

Figure 3 shows another modification of the invention of Figure 1, and,

Figure 4 shows a still further modification of Figure 1.

In Figure 1 the device comprises a body element 1 which is adapted to fit the unit or finger to be protected and may be made of thin rubber, 30 paper like material, or any other type of very thin flexible and yielding or semi-yielding material that is liquid-proof, and should be similar in material, form and shape to that described in my patent referred to above.

Similarly as described in my prior patent, an 35 elastic ring 2 is applied to the side of the body element, preferably below the half of the top closed end. This ring is preferably flat or semi flat and thin, but of sufficient elastic and extensible characteristic, so that when it is drawn over the top of the finger element 1 and put in position somewhere between the open end and the middle portion of the body, it will draw the material of the cover itself, that is the element 1, towards the body that is being covered and form 40 a good seal as is necessary and desirable in this type of device. The ring 2 therefore in its natural and unstretched position is smaller than the diameter of the finger itself at the point where 45 the ring is to be applied. The ring is preferably attached to the body 1 by means of the small disc 4 which may be formed of rubber or other suitable material and which, if not an integral portion of the ring itself, may be attached by 50 cement or any other suitable means to the ring 2.

The disc 4 in turn is cemented to the body portion 1 by rubber cement, or other suitable cement, and is positioned in such a way that the ring is symmetrical with the vertical center line of the finger element as seen in the position indicated in Figure 1 of the drawing. The disc 4 as indicated in the figure is on the under side of the ring 2, that is, in face to face relationship with the surface of the body portion 1. On the opposite end of the diameter from that where the ring is attached to the body, there is positioned a tab or projecting element 3 which projects from the ring 2 and which allows the ring to be drawn over the top end 5 of the finger without the user actually touching either the ring or the cover. Both the tab or extending portion 3 and the disc 4 may be of the same material as the ring 2 in which case if the form of the ring is as indicated in Figure 1, it may be preferably stamped or molded.

The construction indicated in Figure 1, not only positions the ring in suitable and desirable position, but also the tab allows the ring to be extended and drawn over the end of the finger most easily. In the form indicated in Figure 2, the ring is directly attached as indicated by the numeral 6 by cement or other suitable means. The tab 7 corresponds and is in the same position as the tab 3 in Figure 1.

Figure 3 shows a form of a ring 8 that may be either molded, stamped or cut. In this case the ring is attached by means of the tab 9, while the tab 10 serves to allow the ring to be drawn over the end of the finger.

In Figure 4 a square tab 11 is used for attaching the ring 12 to the body or finger 13. In this modification the tab 11 which is square in shape, extends as in Figure 1 on the inside of the ring itself and comes into face to face relationship with the body portion 13 of the finger.

Having now described my invention, I claim:

1. In combination with a surgical finger of the type described, an elastic ring of yielding extensible material, means for attaching said ring to said finger, said attachment positioning said ring with the diameter of the ring through said attachment substantially parallel to the lengthwise dimension of said finger and an extension formed outwardly at the other end of said diameter at the periphery of said ring.

2. In combination with a surgical finger of the type described, an elastic ring of yielding, extensible material having outwardly extending tabs on opposite ends of the same diameter, means attaching said ring to said finger on one of said tabs.

tabs with said diameter positioned lengthwise of said finger.

3. In combination with a surgical finger of the type described, constructed of yielding, extensible thin paper-like material, an elastic ring having a normal unstretched dimension smaller than the dimension of the surgical finger, means for attaching said ring to said finger at only one point thereof and means forming an extension from the

edge of said ring at the opposite end of the diameter through the point of attachment for grasping the same and drawing said ring over the end of the surgical finger, said means being positioned at a point on said ring away from the point of attachment of said ring to said finger and extending outwardly of said ring.

S. IRVING COPEN.
